FOREIGN PATENT DOCUMENTS

AO 2-180400 7/1990

Primary Examiner — Celia A Murphy*Assistant Examiner* — John Windmuller(74) *Attorney, Agent, or Firm* — Oblon, Spivak, McClelland, Maier & Neustadt, L.L.P.(57) **CLAIM**

The ornamental design for an exhaust pipe member, as shown and described.

DESCRIPTION

FIG. 1 is a perspective view of an exhaust pipe member; FIG. 2 is a front elevational view thereof; FIG. 3 is a plan view thereof; FIG. 4 is a left side elevational view thereof; and, FIG. 5 is a sectional view taken along the line 5—5 in FIG. 3. The rear view, the bottom view, and the right side view are the same as the front view, the plan view, and the left side view, respectively. In FIG. 5, only the innermost and outermost circles are part of the claimed design. The area in broken lines between them forms no part of the claimed design. The article to which the design is applied relates to an exhaust pipe member that is mainly used for releasing exhaust gas emitted from an internal combustion engine such as an automotive engine to the rear of the body of an automobile.
